CLAIM

The ornamental design for a cart corral as shown and described.

DESCRIPTION

FIG. 1 is a front perspective view of a cart corral showing our new design;

FIG. 2 is a back perspective view thereof;

FIG. 3 is a right side view thereof, the left side view being identical;

FIG. 4 is a front view thereof, the back view being identical; and,

FIG. 5 is a top view thereof.

The broken lines shown in the drawings are included for purposes of illustrating portions of the cart corral and form no part of the claimed design.

1 Claim, 4 Drawing Sheets
